UNITED STATES PATENT OFFICE.

LEONARD E. RANDECKER, OF ERIE, PENNSYLVANIA.

PULP BEATER.

Application filed August 25, 1921. Serial No. 495,184.

To all whom it may concern:

Be it known that I, LEONARD E. RANDECKER, a citizen of the United States, residing at Erie, in the county of Erie and State of Pennsylvania, have invented certain new and useful Improvements in Pulp Beaters; and I do hereby declare the following to be a full, clear, and exact description of the invention, such as will enable others skilled 10 in the art to which it appertains to make and use the same, reference being had to the accompanying drawings, and to the letters of reference marked thereon, forming part of this specification.

15 My invention relates to paper pulp beaters in which the pulp is placed in a vat and caused to circulate through the beating mechanism until the fibres are thoroughly masticated and ready for the paper machine.

20 The object of my invention is to provide a beating cylinder which co-acts with a stationary member around the entire circumference of the beating cylinder and combining it with a vat in such a manner that the pulp will circulate from the vat through the beating mechanism and thence back into the vat, thus increasing the beating capacity of the apparatus, as well as reducing the 25 demand for power in its operation.

In carrying out the object of my invention I provide a vat, of suitable size to contain a batch of "stuff", which has an opening in the bottom thereof which communicates 35 with the housing of a beating cylinder so that the stuff in the vat will flow into the beater axially and enter between the circumference of the beating cylinder and the housing, and be acted on by the entire circumference of the cylinder, and will be discharged from the beater through a suitable conductor back into the vat.

40 These and other features of my invention will be hereinafter fully described and 45 pointed out and are illustrated in the accompanying drawings, in which—

Figure 1, is a central section of a beating apparatus embodying my invention.

Figure 2, is a transverse section on the 50 line 2—2 in Fig. 1.

Figure 3, is a horizontal section of a portion of the same on the line 3—3 in Fig. 1, looking downward.

55 In these drawings A indicates a vat for the reception of pulp and water, commonly called "stuff," said vat having an opening

A' in the bottom thereof. Secured to the bottom of the vat, is a housing B of a beating machine; said housing having preferably a conical inner surface, which is filled 60 with cutting bars b. The lower end of this housing is provided with an impeller chamber B'. Within this housing I place a cylinder C, which is preferably conical in shape, to correspond with the shape of the 65 housing B, this cylinder C being provided with spaced cutting bars c. Below the cutting bars the cylinder is preferably provided with impeller blades c', which act to force the stuff, after it passes downward 70 through the cutting bars, forward through the return pipe D and thence back into the vat. The beating cylinder is provided with a shaft E, which extends downward through an opening in a closure plate F, secured 75 upon the lower or open end of the housing B.

The shaft E is mounted in suitable bearings E', supported on brackets E'', secured on the plate F. Upon the shaft E I place a 80 driving pulley by means of which power is applied in the usual manner. Under the lower end of the shaft E is placed a thrust bearing G, which is engaged by an adjusting screw H, which is mounted in a cross-bar H' secured to the brackets E'' so that by means of the screws H, the conical beater 85 can be raised or lowered with relation to the stationary cutting bars b, in the housing B.

Within the vat A is placed a shaft J, 90 which carries a suitable agitator frame J' with which the mass of stuff in the vat can be kept thoroughly mixed before it enters the beater mechanism.

In operation the stuff enters preferably, 95 by gravity, into the beating machine, where-in the cutting bars b and c around the entire inner perimeter of the housing B and circumference of the conical beater C act to thoroughly masticate the stuff; the conical 100 shape of the beating cylinder tending to aid the downward flow of the stuff, and the impeller wings c' on the cylinder, finally forcing the stuff to enter the pipe D and flow therethrough back to the vat A. In this 105 circulation the total elevation of the stuff by the mechanism is practically only the distance the pipe D extends above the level of the stuff in the vat A, which, added to the friction of the stuff in passing through the 110 pipe D represents the power necessary to maintain circulation of the stuff through

the apparatus, which is much less than the power expended to maintain the circulation in vat beaters in ordinary use, so that the most of the power necessary to operate my improved beater apparatus is exerted upon the beater cylinder, and is used only in the cutting process, and as the entire cylinder is constantly performing the cutting operation the time consumed in beating a predetermined mass of pulp by my invention is very materially shortened.

Having thus fully described the construction and operation of suitable mechanism to embody my invention, I do not desire to limit myself to the exact construction and arrangement shown, but what I claim as new is:—

1. In an apparatus of the class described, a beater having a conical grinding member

therein, and adapted to grind around its entire surface, a vat adapted to contain a batch of stuff above said beater having an opening in the bottom thereof communicating with the intake end of said beater, a conductor pipe leading from said beater back to said vat adapted to receive stuff from said beater and convey it back to said vat.

2. In an apparatus of the class described, a vat having an opening in the bottom thereof, a rotating agitator mounted in said vat, a beater under the opening in said vat and communicating therewith, and a conveyor adapted to receive stuff from said beater and return it to said vat.

In testimony whereof I affix my signature.

LEONARD E. RANDECKER.
